TUBULAR CONTAINER

Elise Schulz, Vienna, Germany; vested in the
Alien Property CustodianApplication July 26, 1938, Serial No. 221,464
In Austria July 28, 1937

2 Claims. (Cl. 221—60)

The invention relates to the shaping and finish of heads and bodies for tubular containers.

The containers met in practice have nearly always a circular or an oval section and a cylindrical shape on account of the fact that with metal, as constructing means, other sections and shapes are well nigh impossible. However, by using a winding process applied to a strip of a suitable material it is possible to produce containers with several corners and to give same the form of cones or pyramids.

According to the invention the sharp or rounded-off edges of the containers with cornered section are reinforced by rills or foldings (outward or inward); by increasing the thickness of the walls e. g. by sticking on bands or by making folds in the strip, by inserting cones or flexible rods, by laying on or impregnating with a solidifying material, etc., so that in case of pressure on the container, e. g. in squeezing out its contents, no deformation will occur which might spoil the aspect. The container section may be irregular, there may be only one plane of symmetry; may be composed of two unequal halves, so as to form a front part distinct from the back part. In this case the back is usually arranged perpendicularly to the plane of symmetry, so that the container may rest on same.

When producing the containers by winding heavier wall thickness is obtainable, so that the body part may be filled with embossings, rills, impressings, gofferings and the like. This treatment of the container body has the advantage that it may be held in the hand more easily. Between the embossed and stamped parts labels and decorations may be applied. The irregularities engendered on the back of these various processes of embossing, pressing, rill making, etc., are eliminated by applying an appropriate material or filling the uneven portions with a suitable stuff. The material embossed, stamped, goffered, etc., may also have a strip of material applied at the rear to present a smooth inner surface. This end is also attained by inserting in the container body an adequate liner. If the embossing, stamping and the like are made on a perfectly smooth surface, a perfectly smooth back is obtained by using a strong and soft strip in several layers.

Conical and pyramid-shaped containers possess the advantage of being more easily stocked and stripped, the packing and transporting costs are lower because they may be piled up to require little space. Furthermore the bodies of such containers are provided with rills or other

notches, to prevent a scouring or rubbing action of the container bodies when they are in contact during transport.

The use of a suitable material for producing containers by winding is of the greatest importance. It is evident that paper alone or combined with thin-rolled foils of aluminium, tin or other materials is not sufficient for withstanding the mechanical and other strains and stresses. Not even impregnation will do in all cases. Better impregnating results are obtained by employing unglued paper if possible.

The material used for the containers must, first of all, be in concordance with the contents so as to be impermeable thereby. Containers holding water or aqueous solutions are preferably made of rubber which is highly recommendable for its impermeability and elasticity. However such materials cannot be employed alone but only in combination with paper, metal foils, etc. Thereby they meet a double requirement: On the one hand they will isolate the contents and protect the container walls against damage; whilst on the other hand they also protect the metal foil particularly the harder and brittler aluminium foil which is often used. When pressing, squeezing and rolling-in the container, these metal foils easily become loosened because of their hardness and their consequent tendency to porosity. The material added will avoid these bad qualities by its strength tenacity, etc. Instead of the thin rubber skin mentioned above some suitable material may be applied such as a rubber solution, which in winding the body may be laid on interiorly. For certain fillings it is advisable to line the interior of the container with a strong metal foil, etc. This lining may either be wound together with the body or be inserted into the finished body in which latter case it will have to be given advantageously the exact shape of the latter.

When shaping the shoulder and the neck of the container, the walls should be protected against damage as far as possible hence it is preferable to replace the stamping process by a spinning process. In spinning the body is placed on a mandrel and rotated with it whilst the pressing tool is applied against the body. In the usual stamping process the body stuck on a mandrel remains at rest where the shaping is done by pressure. Before spinning the body of the container is formed into several folds so that the subsequent spinning will yield a uniform development of shoulder and neck. After spinning a stamp is used for smoothing the surface. It is

possible and economical to carry out the spinning process on the body winding machine, eventually by working on both sides of the body which is then cut in two. The spinning may be executed by means of knives, rolls, etc., or, for particularly avoiding any damage of body material, by means of belts or other suitable means. The roll or other tool will show the profile required for the operation desired. This method permits dispensing with costly presses and complicated tools, while at the same time rendering possible the production of containers of the largest dimensions, without excessive expense and by means of simple tools.

Special attention should be given to the execution of the container shoulder and neck, which are the most important parts exposed to the heaviest stresses. For strengthening these parts it is advisable to employ a cap or a cover, which is placed on the portion of the container where the body is reduced to form the neck, that is on the shoulder. The aspect of the container is thus improved as the irregular folds formed in the reduction are covered. The rim of the cap or cover leaf may either rest on the shoulder or be made to protrude beyond the adjoining part of the body. In any case it is advisable to sink it into the material of the container, which at these spots shows rills, contractions and the like, so that it avoids, or only slightly projects over the surface of the tube body and is not liable to become loose or damaged. For stiffening this rill, etc., on the protruding part it is contemplated to insert a ring or another staging means. The upper part of the body or the portion of the cap drawn over the shoulder or the ring fixed at that place are preferably knurled or fitted with an embossed stamping, etc., whereby a resting place is offered to the hand in opening and closing the container.

For reducing the body toward the neck, folds are made in the container material, obliquely arranged in the radial direction. For smoothing the shoulder made uneven by the folds formed, a filling material such as gypsum, glue or paste may be introduced into the rills between the folds.

The containers may be equipped with a permanent head or closing part into which the inner container holding the filling is exchangeably inserted and detachably connected. According to the invention the inner container reaches to the neck of the rigid head which eventually overlays the body. The execution indicated renders it possible to pay a special attention to the closing part (stopper) both in regard to the design and aspect. The stopper may be made to be absolutely sealing and the cap be fastened to the body of the container in any manner desired. For the closing part (stopper) and the cap valuable material may be employed e. g. silver and these parts may also be embellished by engraving, carving or in any other manner.

The insert container is connected to the head or stopper and to the outer envelope in a suitable manner e. g. by threads. The threads may be impressed into the container material but it is likewise possible to provide cheap screwing devices made e. g. from aluminium sheets, which are preferably screwed into a threaded part of the closing piece.

The insert container is supplied filled and closed so that drying out is impossible. For use, the delivery end of the insert container is opened by piercing.

The drawings show various embodiments of the invention:

Figs. 1 and 2 are two embodiments of a several cornered container in cross section,

Fig. 3 is a several cornered conical container with irregular cross section,

Fig. 4 is a conical container with pressed-on neck,

Fig. 5 is a container with a shoulder reinforced by a cap shown in section,

Fig. 6 is an end view of the arrangement of the folds on the shoulder of Figure 5,

Fig. 7 is an embodiment of a permanent head before its connection with the container body,

Fig. 8 is a broken elevation, partly in section, of a container with permanent head and with the container body joined to the container head,

Fig. 9 is a container body with permanent head and an outer envelope.

The hexagonal container body as in Fig. 1 has edges reinforced by outer rills 1, the container in Fig. 2 having inner rills 2.

Fig. 3 shows a container with several cornered cross section, having only one symmetry plane S, whereby the plane 3 intersecting the plane of symmetry perpendicular to the latter, forming the back of the container, on which the latter will usually rest and which may if desired carry printed instructions. The front face 4 may be employed for advertising purposes.

Fig. 4 shows a pyramidal container on whose reduced end 5 a neck 6 is applied by pressure.

The container body as per Fig. 5 carries on the body a cap 9 constituting a reinforcement of the body and used as cover for the folds 1. The rim of the cap 9 terminates at the upper portion of the body near the shoulder 10 and is recessed into the container body, the latter forming a protruding rill 11 which is flush with the cap rim. Into that rill a stiffening ring may be inserted. On the lower portion of the figure the rim 12 of the cap 9 is slightly drawn down over the rim between shoulder and container body and is likewise set into the container body so that the cap rim and the body form one single plane. The rim 12 is preferably knurled so as to enable the container to be firmly grasped when operating the closing device.

The permanent container in Fig. 7 shows a permanent closing piece or head 11 made from a more solid and if desired valuable material, which on the neck is provided with outer and inner threads, the outer threads 12 for screwing on the closing piece and the inner 13 for fixing the insert container body 14 introduced from below in the direction of the arrow, the insert container body being provided on the neck 15 with a threaded aluminium ring 16 to cooperate with the threaded portion 13.

The second embodiment of the permanent container (Fig. 8) consists of a head 15' and the insert container body 16' which is screwed into the threaded part 18 of the head 15' by means of threaded ring 17. The insert container 16' is to be tightly sealed by a permeable piece 19 to be pierced when desired.

In the permanent container as per Fig. 9 an outer envelope 21 is screwed on to the permanent head 11 to which head the insert container body 14 is secured. The outer envelope consisting of three parts telescopicly displaceable in respect to one another so that it may at any time be adapted to any decreased length of the insert container as to protect the latter against damage, etc.

I claim:

1. A container including a body having a conical end and formed with a peripheral recess below such end, and a head section of relatively rigid material conforming in shape to the end of the body and seated in the recess in the body to prevent projection of the head section beyond the outer plane of the body.

2. A container having a body made up of elastic impermeable material, the material of the body in excess of the material required for the

5 formation of the body, being folded in external pleats on the upper end of the body, and an end section of relatively rigid material conforming in shape to the upper end of the body and seated in a recess in the body formed below the upper end to prevent projection of the end section beyond the outer plane of the body below such section, the end section overlying and concealing the pleats.

ELISE SCHULZ.
